BY *R. Newell.*

his ATTORNEY,

UNITED STATES PATENT OFFICE.

JULIUS ENGEL, OF NEW YORK, N. Y.

NECKTIE-RETAINER.

SPECIFICATION forming part of Letters Patent No. 393,101, dated November 20, 1888.

Application filed May 22, 1888. Serial No. 274,758. (No model.)

To all whom it may concern:

Be it known that I, JULIUS ENGEL, a citizen of the United States, residing at the city of New York, in the county and State of New York, 5 have invented a certain new and useful Improvement in Retainers for the Bands of Neck-scarfs, of which the following is a full, clear, and exact specification, reference being had to the drawings accompanying and forming a 10 part of the same.

My invention has relation to devices for holding the bands of neckscarfs in a proper position on the collar; and my improvement consists of a retainer for preventing the upward displacement of the band, which is capable of being secured to the scarf or necktie band without the usual means of sewing the same to or within the band or clamping it thereon, its method of attachment being such 15 that it can be introduced into the band without disturbing the finely-stitched edge thereof, all as will be more fully hereinafter set forth.

In the accompanying drawings, which clearly illustrate the novel features of my improved retainer, Figure 1 is a perspective view of one of my improved retainers, shown 20 considerably enlarged; and Fig. 2 is an enlarged sectional view of the neckband, showing the retainer applied to the band and collar.

Let A represent the neckband of a scarf or cravat, b the collar, and c, in general, the device for holding the band in the proper position on the collar and preventing it from rising upward at the back of the neck. The 25 neckband A is formed with an outer strip, a, and an inner strip, a', the edges being turned in and united by stitching the two together in the usual manner. The retainer c, as constructed by my improvement, is adapted to 30 be secured within the stitched band without additional sewing and without clamping, both of which methods of attachments are objectionable in a more or less degree. The retainer or holder c is preferably formed out of 35 a single flat strip of metal. This strip is folded or doubled back on itself, one of its members serving as the hook on the outside of the band, which receives the lower edge of the collar, as shown in Fig. 2. The other 40 member is formed so that it may be passed through the stitched seam of the band and be

locked therin without penetrating the material of which the band is composed. The strip of metal is turned down on itself, so as to produce a slightly projecting or overhanging bend, as seen at d, and from this point of curvature the strip is bifurcated to form two long prongs, f, which are made with slightly tapering and rounded ends to facilitate their insertion through the stitched edge of the 50 band.

On the outer edge of each prong and below the band is provided an upwardly and backwardly turned spur or hook, h, whereby a tapering recess is formed on the edge and near 55 the top of each prong. The short spurs or hooks h are made to spread out from the prongs, so that when the prongs are inserted between the turned-in edges of the two strips which compose the band the spurs or hooks 60 will be made to adjust themselves between the outer strip, a, and its inner turned-down edge, which latter is held between the spurs or hooks and prongs, as shown in Fig. 2.

The prongs f are made narrow enough to 65 permit of their being inserted through the spaces between the stitches on the edge of the band.

In adjusting and securing the retainer on the band each prong is inserted in between 70 a stitch on the seamed edge of the band and then both pressed down as far as the enlarged bend and the spurs or hooks h will allow, when by a slight pressure, first on one side 75 and then on the other, in an oblique direction, 80 both hooks h may be sprung down between the stitches and within the band, the enlargement in the bend causing a slight expansion of the seam to facilitate the insertion of the upturned spurs or hooks. When the device 85 is adjusted in the band, the spurs or hooks 90 will be forced up so as to lie between the outer strip, a, and its inclosed edge, where they will be held by the seamed edge, the reversed hooks locking the retainer in the band, so that 95 it cannot be withdrawn therefrom without ripping the edge of the band.

Having now described my invention, what I claim as new, and desire to secure by Letters Patent, is—

1. A retainer for the neckband of a scarf or cravat, formed of a strip of metal doubled or

folded upon itself and having one of its members provided with the flat prongs and upwardly-turned spurs or hooks on said prongs, as and for the purpose set forth.

5 2. A neckband-retainer consisting of a strip of metal bent at about its middle, with an outwardly-enlarged curve, and having one of its members bifurcated and provided with up-

turned spurs or hooks on said prongs adapted to take over the inclosed seamed edge of the band, substantially as set forth.

JULIUS ENGEL.
